United States Patent Office.

WILLARD M. CARPENTER, OF ROWLEY, MASSACHUSETTS.

Design No. 4,646, dated February 14, 1871.

DESIGN FOR AN INFANT'S SHOES.

The Schedule referred to in these Letters Patent and making part of the same.

I, WILLARD M. CARPENTER, of Rowley, in the county of Essex and State of Massachusetts, have invented a new and original Design for Infants' Shoes, of which the following is a specification.

Figure 1 is a perspective view of my invention.

Figures 2 and 3 are plan views of the vamp and counter.

The nature of my design consists mainly in providing the upper of the shoe with ornamental perforations of any desired shape and size, thereby exposing to view the lining, which is of a color contrasting harmoniously with that of the leather or other material of which the upper is composed; also, in the peculiar shape of the heel-counter, the same being highest at the back and provided with a scalloped edge; also, in providing the vamp at the instep with a similar edge.

In the drawing—

A represents the "upper" of the shoe, which is composed of the vamp B and counter C, both of which are provided with the scalloped edge D, near which are perforations E.

The counter and vamp are provided with perforations F, which are arranged in the ornamental form shown.

The upper A is composed of leather, &c., of any

ornamental color, and lined with a material of a contrasting color, thus giving to the perforations E F an ornamental effect, which is heightened by stitching, G, which is composed of silk or thread of a color contrasting to that of the upper, preferably corresponding to that of the lining.

A rosette, H, composed of scalloped material corresponding in color to the upper A, is attached to the same at the instep.

The perforations E F afford ventilation to the foot through the fibrous lining.

Having thus fully described my invention, What I claim as new, and desire to secure by Letters Patent, is—

The design for an infant's shoe, substantially as shown and described.

In testimony whereof I have signed my name to this specification in the presence of two subscribing witnesses.

WILLARD M. CARPENTER.
